DRESSING MECHANISM FOR GRINDING WHEELS

Harold N. Seyferth, East Detroit, Mich., assignor to Ex-Cell-O Corporation, Detroit, Mich., a corporation of Michigan

Application November 3, 1943, Serial No. 508,774

7 Claims. (Cl. 125—11)

The present invention pertains to a novel dressing mechanism for grinding wheels.

One object of the invention is to provide such a mechanism embodying a plurality of dressing tools for dressing respective portions of the wheel, such as its peripheral edge and flanks, and in which a simple reciprocal slide arrangement serves to actuate all of the tools in timed relation in their respective paths, while affording independent angular adjustment for the path or paths of the flank dressing tool or tools.

Another object is to provide a dressing mechanism of the character indicated which is especially suited for drive from a remote point, either by power or by hand crank or the like.

The invention also resides in various improvements in, and novel correlation of, the parts of the mechanism by means of which simplicity and ruggedness of construction, as well as adaptability to a wide variety of wheel sizes and shapes, are achieved.

Further objects and advantages of the invention will become apparent as the following description proceeds, taken in connection with the accompanying drawings in which:

Figure 1 is an end elevation of a dresser mechanism embodying the invention, the same being shown in conjunction with a portion of a grinding wheel upon which it is adapted to operate.

Fig. 2 is a plan view of the dresser mechanism of Fig. 1, and also includes a fragmentary portion of the grinding wheel.

Figs. 2a and 2b are fragmentary stop motion views showing, in conjunction with Fig. 2, successive positions occupied by the several dresser points.

Figs. 3, 4 and 5 are fragmentary detail sectional views taken substantially along the lines 3—3, 4—4 and 5—5, respectively, in Fig. 2.

Fig. 6 is a rear elevation, partially in section, of a dresser mechanism of Figs. 1 and 2.

Fig. 7 is a transverse sectional view taken substantially along the line 7—7 in Fig. 2.

Fig. 8 is an exploded perspective view showing various principal parts of the dresser mechanism.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit

and scope of the invention as expressed in the appended claims.

Referring more particularly to the exemplary embodiment of the invention illustrated in the drawings, the device there shown (see Figs. 1 and 2) embodies three diamond point dressing tools 10, 11 and 12 adapted to dress or true, respectively, the peripheral edge and sides or flanks of a grinding wheel such, for example, as 10 that designated generally by the numeral 13. In performing this operation the dresser is adapted to move all three of the tools in timed relation to each other, each of them being reciprocated in its own individual path. The tool 10 is reciprocated back and forth across the edge of the wheel to true it to flat contour, while the tools 11 and 12 move along angularly related paths to true the respective flanks of the wheel. As the tool 10 is being stroked from the position of Fig. 15 to 2 that of Fig. 2a, the tool 11 simultaneously moves outward of the wheel along the adjacent wheel flank, while the tool 12 moves in the opposite or inward direction along the flank adjacent to it, such motion of the three tools being continued to the position indicated in Fig. 2b, whereupon the motion of all three is reversed.

Interference of the tools with each other is prevented by timing the flank dressing tools 11, 12 so that the one of them toward which the center tool 10 is approaching is moved away from such center tool and the other flank dressing tool moved generally toward the center tool. Broadly speaking, the motion of the tools is such that they trail one after another back and forth 35 around the edge of the wheel although each operates on only its own assigned portion of the wheel periphery.

As will hereinafter appear, provision is made for adjustment of the angularity of the paths of the flank dressing tools 11 and 12 and the relative positions of all three tools to accommodate wheel peripheries of correspondingly varied contours as, for example, in conditioning the wheel 13 for grinding threads of different profile.

To support the dresser mechanism as a unitary structure adapted for ready attachment to, or detachment from, the machine, a bracket 14 (Fig. 1) is utilized, the same being secured by bolts 15 to a portion of the machine bed indicated at 16. The bolts are received in longitudinal slots 15a in the bracket to accommodate endwise adjustment of the latter. Arcuate bearing members 17 (see also Figs. 3 and 6) on the bracket 14 receive trunnions 18 which are rigid 50 with opposite ends of a support or body member

19 (see Fig. 8 for detail of shape of the latter). This trunnion mounting of the support 19 makes possible angular adjustment of the support about a longitudinally extending axis passing through the centers of the trunnions, such adjustment being utilized in accommodating the dresser mechanism to wheels of different diameters, as will hereinafter appear. To hold the support 19 in various positions of its angular adjustment, locking means is provided for each of the trunnions 18. Such locking means comprises screws 20 (Figs. 1 and 3) passing through holes 21 in the arcuate bearing members 17, as well as through registering arcuate slots 22 in the trunnions, the inner ends of such screws being threaded in plugs 23 which are received in longitudinal bores within the respective trunnions. The plugs, in effect, form T heads on the screws 20 so that when the latter are tightened, the trunnions 18 are pulled tightly down against their bearing seats.

Flattened top surfaces 18a on the trunnions 18 support a main slide 24 for reciprocation longitudinally of the support 19 in a path paralleling the axes of the trunnions 18. Housing blocks 25, 26 bolted to respective ones of the trunnion faces 18a are recessed to receive and guide the slide 24. Reciprocation of the slide 24 is effected by means of a screw 27 threaded within an opening 28 in one end of the slide (Figs. 2, 6 and 8), the screw being journaled within the housing 25 and restrained against axial displacement relative thereto. A flexible shaft 29 is attached to the screw 28, and any suitable reversible means (not shown) may be used for revolving the shaft first in one direction and then in the other to reciprocate the slide. Since the drive is derived by way of a single flexible shaft, the source of power, whether a manually operated device or motor, may be located at any convenient point on the machine, either close to the dresser mechanism or remote from it.

The center dressing tool 10 is carried by the main slide 24 and thus reciprocated directly by it. For that purpose the tool 10 is received in a mounting block 30 provided with a dog screw 31 for fixing the tool in various adjusted positions of projection of the same with respect to the mounting block. The block itself is fixed to the intermediate portion of the slide 24.

The two flank dressing tools 11 and 12 are carried on respective auxiliary slides 32, 33 (Fig. 2) reciprocable along coplanar dovetail guides 34 (see also Fig. 4) fashioned on the upper sides of individual intermediate supporting members 35, 36. The intermediate supporting members 35, 36 project generally laterally outward at one side of the main slide 24 and are individually angularly adjustable on the main support or base 19. For that purpose the intermediate supporting members 35, 36 are pivoted on the main support 19 by bosses 40 on their undersides and which are received in depressions 39 in the support 19 (Figs. 4 and 5). Bolts 37 passing through holes 38 centered in the recesses 39 (see Fig. 8) serve to hold the auxiliary slides 32, 33 in their positions of selected angular adjustment. The usual plates 41 (Fig. 4) are provided for securing the auxiliary slides 32, 33 in position on their dovetail guides 34.

The flank dressing tools 11, 12 are adjustably secured within and project laterally from the respective auxiliary slides 32, 33. Accordingly, these tools are moved through straight line paths as their respective slides are reciprocated along

the dovetail guides 34, such paths lying in a common plane.

To alter the angularity of the path of movement of either of the flank dressing tools 11 or 12, the bolt 37 for its corresponding auxiliary supporting member 35, 36 is loosened and the auxiliary support turned about its pivot 39, 40 to the desired angular position. A direct reading of the angular adjustment of each of the flank dressing tools 11, 12 is afforded by graduated scales 42 (Fig. 2) on arms 43 fixed to the housings 25, 26 and overlying the auxiliary slides 32, 33 on which are scribed index lines 44 coacting with the scales. The scales 42 are concentric with the pivots 39, 40 for the respective auxiliary slide supports.

To reciprocate the auxiliary slides 32, 33 in timed relation with the main slide 24, a cam mechanism for driving the auxiliary slides directly from the main slide is provided. This cam mechanism comprises a cam projection integral with the underside of the slide 24 and presenting a flat cam face 45 (Figs. 2, 6 and 8) extending generally transversely of the path of reciprocation of the slide but at an acute angle with respect thereto. An opposed and oppositely angled flat cam face 46 is provided on a block 47 adjustably secured to the recessed underside of the slide 24 by a screw 48 passing through a longitudinal slot 49 in the slide and threaded in a tapped hole in the block. As will be seen upon reference to Fig. 2, the cam faces 45, 46 are thus arranged to diverge from each other in a direction opposite to the divergence of the guides 34 for the auxiliary slides 32, 33 so that the guides 34 are approximately normal to their respective cam surfaces.

Coacting with the cam surfaces 45, 46 are cam follower rollers 50, 51 journaled on the inner ends of the respective ones of the auxiliary slides 32, 33. The auxiliary slides are yieldably urged outward by compression springs 52 in a direction to retain the follower rollers 50, 51 in engagement with the respective cam surfaces. For that purpose each of the compression springs 52 is coiled about a rod 53 threaded at its inner end in the respective one of the auxiliary supporting members 35, 36 (see Fig. 5). The rods 53 pass through openings in end plates 54 screwed to the ends of auxiliary slides 32, 33. The springs 52 are interposed between opposed faces on the supporting members 35, 36 and the end plates 54, outward movement of the auxiliary slides 32, 33 under the urging of the compression springs 52 being limited by stop nuts 55 threaded on the rods 53. As the main slide 24 reciprocates the followers 51, 52 are thus constrained to move along the respective inclined cam faces 45, 46, carrying the auxiliary slides 32, 33 with them so that the latter slides are reciprocated reversely with respect to each other and in timed relation with respect to the main slide.

By providing the cam face 46 on the adjustable block 47, the spacing between the cam faces 45, 46 may be varied to accommodate adjustment changes in width of the wheel contour or different relative angular positions of the auxiliary slides 32, 33, while still retaining the flank dressing tools 11, 12 located with predetermined displacements relative to the center dressing tool 10.

As heretofore indicated, the flank dressing tools 11, 12 are reciprocated in straight line paths lying in a common plane, and in order that they shall cut straight-sided flanks on the grinding

wheel 13 it is requisite that this plane pass through the axis of rotation of the grinding wheel. Location of this plane is indicated by the line X—X in Fig. 1. It is to facilitate retention of that relation, with changes in wheel diameter, that provision is made for angular adjustment of the dresser support 19 about its longitudinal axis through the use of the trunnions 18 heretofore described. Upon reference to Fig. 1, it will be seen that if the diameter of the wheel 13 is decreased so that its periphery occupies the position indicated by the dot-dash line 13a that the axis of rotation of the grinding wheel will be displaced to the left along the horizontal line L—L if its point of contact P with the work remains fixed. With such change in the location of the wheel axis, it is necessary to turn the dresser support 19 counterclockwise (as viewed in Fig. 1). To facilitate such adjustment a scale 56 may be provided on the end of one of the supporting bearings 17 to coact with an index line 57 scribed on the adjacent trunnion end face and calibrated in terms of wheel diameter.

The operation of the disclosed dresser mechanism will, in general, be clear from the foregoing. By way of recapitulation, it may be noted that the angular position of the dresser support 19 is initially adjusted to accommodate the wheel diameter and the respective angular positions of the auxiliary slides 32, 33 are initially adjusted to conform with the angularity of the flank surfaces to be dressed on the wheel. The projection of the several dresser points from their holders is also adjusted initially to conform with the wheel contour to be dressed.

Having effected such preliminary adjustments, it is only necessary to revolve the drive screw 27 by means of the flexible shaft 29 first in one direction and then in the other sufficient distances to reciprocate the main slide 24 through a full stroke forward and then back to the starting point in order to operate the dresser. Such reciprocation of the main slide carries the center dressing tool 10 back and forth across the edge of the grinding wheel, dressing the same. At the same time the cam surfaces 45, 46 on the main slide coat with the cam follower rollers 50, 51 to reciprocate the flank dressing tools 11, 12 reversely with respect to each other and in timed relation with the center dressing tool 10. As the center dressing tool moves progressively from the position of Fig. 2 through that of Fig. 2a to the position of Fig. 2b, the tool 11 moves outward of the wheel toward the main slide of the dresser mechanism along its corresponding flank of the wheel, while the other flank dressing tool 12 moves inward in the opposite direction. In the return stroke of the main slide 24 each of the tools moves reversely, passing successively from the positions of Fig. 2b, through those of Fig. 2a, to the initial position shown in Fig. 2.

I claim as my invention:

1. A dressing mechanism for grinding wheels comprising, in combination, a support, a plurality of dressing tools and a corresponding plurality of slides carrying the same, means mounting a first one of said slides on said support for reciprocation in a fixed rectilinear path, means mounting a second one of said slides on said support for reciprocation in a rectilinear path angularly related to the first-mentioned path, and means including coacting cam and cam follower elements carried by the first and second slides for

reciprocating said second slide in timed relation with reciprocations of the first.

5 2. A dressing mechanism for grinding wheels comprising, in combination, a support, a plurality of dressing tools and a corresponding plurality of slides carrying the same, means mounting a first one of said slides on said support for reciprocation in a fixed rectilinear path, adjustable means mounting a second one of said slides for reciprocation in a path bearing an adjustable angular relation to the first-mentioned path, and means including coacting cam and cam follower elements carried by the first and second slides for reciprocating said second slide in timed relation with reciprocations of the first.

10 3. A dressing mechanism for grinding wheels comprising, in combination, a support having a main slide reciprocable thereon, a pair of auxiliary slides mounted on said support for reciprocation in individual paths lying in a common plane and generally angularly related to each other, said paths extending laterally from one side of the path of reciprocation of said main slide, individual dressing tools carried by each of the aforementioned slides, and means for adjusting said support angularly about an axis paralleling the path of reciprocation of said main slide.

15 4. A dressing mechanism for grinding wheels comprising, in combination, a support having a slide reciprocably mounted thereon, a first dressing tool carried by the slide and projecting laterally thereof in a direction generally transverse to the path of reciprocation of such slide, cam means rigid with the slide and presenting a pair of opposed cam surfaces extending angularly across the slide's path of reciprocation, a pair of angularly adjustable intermediate supporting members carried by said support, auxiliary slides having individual dressing tools thereon and reciprocably mounted on respective ones of said intermediate supporting members, cam followers connected to respective ones of said auxiliary slides, and means for yieldably urging said cam followers into engagement with respective ones of said cam surfaces.

20 5. A dressing mechanism for grinding wheels comprising, in combination, a support having a slide reciprocably mounted thereon, a first dressing tool carried by the slide and projecting laterally thereof in a direction generally transverse to the path of reciprocation of such slide, cam means rigid with the slide and presenting a pair of opposed cam surfaces extending angularly across the path of reciprocation of such slide, a pair of angularly adjustable intermediate supporting members carried by said support, auxiliary slides having individual dressing tools thereon and reciprocably mounted on respective ones of said intermediate supporting members, scale and reference elements on said support and said intermediate slides coacting to indicate the individual angles of adjustment of said intermediate supporting members, cam followers connected to respective ones of said auxiliary slides, and means for yieldably urging said cam followers into engagement with respective ones of said cam surfaces.

25 6. A dressing mechanism for grinding wheels comprising, in combination, a support having a slide reciprocably mounted thereon, a first dressing tool carried by the slide and projecting laterally thereof in a direction generally transverse to the path of reciprocation of such slide, cam means rigid with the slide and presenting a pair of opposed cam surfaces extending generally an-

gularly across the path of reciprocation of the slide, a pair of intermediate supporting members each having a guideway extending longitudinally of the same, means for pivotally mounting said intermediate supporting members on said support at one side of said slide with said guideways projecting generally laterally outward from said slide divergently from each other in a common plane, the angles at which said intermediate supporting members project outwardly from said slide being individually adjustable by turning the same on their pivotal mountings, auxiliary slides having individual dressing tools thereon and reciprocably mounted on respective ones of said intermediate supporting members, cam followers connected to respective ones of said auxiliary slides, and means for yieldably urging said cam followers into engagement with respective ones of said cam surfaces.

7. A dressing mechanism for grinding wheels comprising, in combination, a support having a slide reciprocably mounted thereon, a first dress-

ing tool carried by the slide and projecting laterally thereof in a direction generally transverse to the path of reciprocation of such slide, said slide having a first cam surface thereon of flat contour extending generally transversely across the slide but at an acute angle to the path of slide reciprocation, a cam member having a second cam surface thereon opposed to the first cam surface and angled away from the same, means for adjustably securing said cam member to the slide with a selectively variable spacing between said opposed cam surfaces, a pair of angularly adjustable intermediate supporting members carried by said support, auxiliary slides having individual dressing tools thereon and reciprocably mounted on respective ones of said intermediate supporting members, cam followers connected to respective ones of said auxiliary slides, and means for yieldably urging said cam followers into engagement with respective ones of said cam surfaces.

HAROLD N. SEYFERTH.
